MAX KIRN, OF SIEMENSSTADT, NEAR BERLIN, GERMANY, ASSIGNOR TO SIEMENS & HALSKE AKTIENGESELLSCHAFT, OF SIEMENSSTADT, NEAR BERLIN, GERMANY, A GERMAN COMPANY.

ELECTRICAL TRANSMISSION SYSTEM.

Application filed June 22, 1926, Serial No. 117,658, and in Germany July 31, 1925.

This invention relates to electrical transmission systems, particularly systems employing quadded cable.

- As is well known in the telephone art, it is often customary to combine two metallic circuits, called side circuits, to give a third circuit, known as the phantom circuit, so that three independent speaking circuits are formed by the use of two pairs of wires. 5
 10 In such systems it is often desirable to employ cables for the transmission line, the two pairs of wires which make up each group of two side circuits and a phantom circuit being known as a quad. 15
 15 In the cables the four wires are stranded together in a particular manner to give a definite characteristic. The most familiar of these stranding systems are the Dieselhorst-Martin and the Star systems. Lines 20 composed of conductors stranded according to either of these systems have the disadvantage that on account of the geometrical arrangement of the conductors, the ratio of the working capacity of the phantom circuit to that of the side circuit is fixed. 25

For many purposes it is desirable to be able to control the ratio of phantom to side circuit capacities. For example, it is important that the attenuation of all the circuits should be equal, so that the repeater spacing established in the side circuits can also be used for the phantom circuits without any modification. Similarly, for economical reasons, the cut-off frequency should be made equal for both circuits. With telephone cables of the type known heretofore the cut-off frequency has necessarily been higher for the phantom circuits than for the side circuits. This is due to the fact that the phantom capacity must be a given multiple of the side circuit capacity when using a single type of stranding. For example, the ratio of phantom circuit to side circuit capacity for the ordinary Dieselhorst-Martin stranding is of the order of 1.5 to 1.7, averaging about 1.6 and with the Star system of the order of 2.7 to 2.9 averaging about 2.8. Moreover, since the ratio of the ohmic resistances of the phantom circuits and the side circuits are fixed and the loading coil spacing for the phantom circuits and the side circuits is usually made equal for eco-

nomic reasons, there has, hitherto, been left only one alternative, that is, to compromise between the attenuation and the cut-off frequencies which were desired. This led to uneconomical conditions. 55

An object of this invention is to control the ratio of the phantom circuit capacity to the side circuit capacity in a quadded cable 60 system.

A further object of the invention is to make the phantom circuit transmission characteristic similar to that of the side circuit transmission characteristic by the use of a 65 simple, economical and practical method.

According to a feature of this invention, lines are composed of sections stranded in different manners so that the ratio of the working capacities can be varied arbitrarily 70 within certain limits. In order that the line may be somewhat similar to a homogeneous line in its effect the sections are preferably chosen to be small with respect to the wave length of the transmitted frequencies. For 75 example, in cables loaded according to the Pupin system, each loaded section should be composed of several differently stranded portions.

In accordance with another feature of this 80 invention the portions of the line stranded according to the different systems are so proportioned with respect to one another as to give the same transmission characteristics for both the phantom and side circuits. 85

In the preferred embodiment of the invention part of the line is stranded according to the Star system and the remainder according to the Dieselhorst-Martin system, the ratio of the portions being determined as 90 explained below to give the desired characteristics. If it is desired to use other methods of stranding the same method of calculating the relative proportions may be used. 95

As stated above it is desirable that:

1. The attenuation of the phantom and side circuits be equal.
2. That the cut-off frequencies for the phantom and side circuits be equal. 100
3. That the loading coil spacing be the same.

As a first approximation it may be assumed that with loaded lines, the attenua-

tion is independent of the leakance. With this assumption it follows that in order to obtain the desired characteristics the following conditions are necessary:

$$C_p = 2C_s$$

$$L_p = \frac{L_s}{2}$$

These give the following ratio of characteristic impedances,

$$Z_p = \frac{Z_s}{2}$$

In these equations C_p , L_p , Z_p and C_s , L_s , Z_s represent the capacity, inductance and characteristic impedance of the phantom and side circuits respectively.

The above ratio of inductances can always be obtained by controlling the loading and according to this invention, by connecting together a certain length of Star stranded cable with a definite proportional length of Dieselhorst-Martin stranded cable, the radio

C_p can be made to approximately equal C_s the value two, and thus fulfill the conditions required by the first equation.

In order to ascertain the relative lengths of the various kinds of cable in each loading section, it may be assumed that the length of the loading section is 1, and the length of the Star stranded cable is X . It therefore follows that the length of the Dieselhorst-Martin stranded cable is $1-X$. Assuming the average values, given above, for the ratios of phantom to side circuits capacities for the two types of cables and that both types of cables have the same side circuit capacities, the ratio of the overall phantom to side circuit capacities is:

$$\frac{C_p}{C_s} = \frac{2.8X + (1-X)1.6}{X + (1-X)}$$

$$\frac{C_p}{C_s} = \frac{X(2.8 - 1.6) + 1.6}{X + (1-X)}$$

$$\frac{C_p}{C_s} = 1.2X + 1.6$$

Since this ratio is required to have the value 2

$$\frac{1.2X + 1.6}{X} = 2$$

$$X = 1/3$$

Therefore in accordance with this invention, one-third of the loading section should be composed of Star stranded cable and two-thirds of Dieselhorst-Martin stranded cable.

These and other features and objects of the invention can be more readily understood by reference to the following detailed

description in connection with the drawing in which: Figs. 1 and 2 illustrate the methods of quadding according to the Dieselhorst-Martin and Star systems respectively and Fig. 3 shows a portion of a transmission line arranged in accordance with this invention.

Fig. 1 shows a quad composed of two metallic circuits, a , a and b , b . In accordance with the Dieselhorst-Martin system these are stranded by first twisting together the two wires making up each pair and then twisting the two pairs together to make a rope of four wires. When more than one quad is combined in a cable, two quads formed as shown are twisted together and so on.

Fig. 2 shows a method of stranding according to the Star system in which a quad composed of two pairs a , a and b , b is stranded by simultaneously twisting the four wires together.

Fig. 3 shows diagrammatically two loading sections 4 and 5 of a transmission system associated with loading coils 6 and 7, respectively. Each of these sections is composed of three sections of cables 8, 9 and 10 and 11, 12 and 13 respectively. Two of these sections in each loading section, for example, 8 and 9 in section 4 and 11 and 12 in section 5 are stranded according to the Dieselhorst-Martin system as shown in Fig. 1 and the remaining section in each loading section (10 and 13) is stranded according to the Star system.

What is claimed is:

1. In a phantomed transmission system, a lumped loaded transmission line in which each loading section comprises a plurality of sections of quadded cable, one-third of the cable sections of each loaded section being quadded according to the Star system and the remainder according to the Dieselhorst-Martin system.

2. The method of controlling the ratio of phantom to side circuit capacities in a quadded cable line which comprises dividing the line into sections short with respect to the wave lengths of the waves to be transmitted and stranding portions of said sections in different manners the lengths of said portions being so proportioned with respect to one another as to give the desired capacity ratio.

3. A method according to the next preceding claim in which said portions are stranded according to the Star and Dieselhorst-Martin systems.

In witness whereof, I hereunto subscribe my name this 27th day of May A. D., 1926.

MAX KIRN.
